[57] CLAIM

The ornamental design for a combined urine meter and urinary drainage bag, as shown.

DESCRIPTION

FIG. 1 is a front elevational view of a combined urine meter and urinary drainage bag, showing my new design;

FIG. 2 is a top plan view thereof;

FIG. 3 is a left side elevational view thereof;

FIG. 4 is a right side elevational view thereof;

FIG. 5 is a bottom plan view thereof; and

FIG. 6 is a rear elevational view thereof.
